CARRIER WITH HANDLE

Floyd L. Phillips, Jr., Lynchburg, Va., assignor to Old Dominion Box Company, Inc., Lynchburg, Va., a corporation of Virginia

Filed June 16, 1961, Ser. No. 117,697

14 Claims. (Cl. 220—112)

The present invention relates to a carrier made of paperboard or the like and, more particularly, to a carrier having a handle and adapted for packaging a rectangular-shaped parallelepiped article or a plurality of such articles.

In present day merchandising practices, many products such as food, granulated soap, and the like are packaged in rectangular-shaped parallelepiped paperboard cartons for retail. As is the current custom, the packager utilizes different-sized cartons for packaging different quantities of a product, it being the practice to reduce the unit price as the quantity is increased. For example, the price of a ten-pound carton will be less per pound than the price of a two-pound carton. Such merchandising procedure has resulted in the cartons becoming unusually large. While such large cartons may be easily transported by the purchaser to the point of use, oftentimes the handling of the carton after it is open is very cumbersome and difficult, thus taking away from the desirability of purchasing a large quantity at a cheaper unit cost.

Further, the retail stores have made it a practice to sell the plurality of cartons of a particular commodity at a cheaper cost per carton than a single carton. However, difficulty is often encountered by the purchaser in transporting the plurality of loose cartons from the point of purchase to the point of use.

An object of the present invention is to provide a carrier made from paperboard or other suitably stiff but flexible fibrous material for packaging a plurality of similar sized rectangular-shaped parallelepiped articles which makes it easier and more convenient to transport multiples of such articles.

Another object of the present invention is to provide a carrier which lends itself readily to the packaging of any rectangular-shaped parallelepiped article or articles which must be transported, the carrier being made from a single blank of paperboard material or the like and readily applied to the article.

Still another object of the invention is to provide a carrier for rectangular-shaped parallelepiped articles in which the articles may be placed for transportation, the carrier being so designed that the contents of the same, namely, the articles being carried, are exposed so that the advertising material on the articles is visible and the articles may be inspected without removal from the carrier.

A further object of the present invention is to provide a carrier made from a paperboard blank or the like which may be collapsed into a relatively flat object when not in use so that a number of the same may be stored in a minimum space, the carrier being capable of quick and easy erection and application to the article or articles which it carries.

Another object of the present invention is to provide a paperboard carrier for parallelepiped articles, the carrier having a handle so arranged that the weight of the articles assists and maintains the carrier on the articles as the articles are being transported.

2

Still another object of the present invention is to provide a paperboard carrier or the like having a handle so positioned thereon that when the carrier is erected and applied to parallelepiped articles, the carrier with its contents may be nested or stacked with other similar carriers without the handle interfering in the nesting of the same.

A further object of the present invention is to provide a carrier for supporting similar shaped articles which operate on the "ice tong" principle, the carrier being further provided with means to assist in holding the articles should the article vary slightly from a standard size.

These and other objects and advantages of the present invention will be more apparent from the following specification, claims and drawings in which:

15 FIGURE 1 is a perspective view of the carrier of the present invention illustrating the same erected and applied to a plurality of rectangular parallelepiped articles;

20 FIGURE 2 is a sectional view looking generally in the direction of the arrows 2—2 of FIGURE 1, the view also illustrating in broken lines a second carrier stacked or nested on the top wall of the first carrier;

25 FIGURE 3 is a perspective view of the carrier of the present invention illustrating the partial application of the erected carrier to the plurality of rectangular parallelepiped articles;

FIGURE 4 is a plan view of the inner face of a paperboard blank used in erecting a carrier of the present invention, the view illustrating the score lines and cut lines of the paperboard blank;

30 FIGURE 5 is an enlarged perspective fragmentary view of a typical corner of either a top wall or bottom wall of the present invention; and

35 FIGURE 6 is a perspective view of the paperboard carrier in its collapsed or folded position for storage or shipping.

Referring now to the drawings wherein like character or reference numerals represent like or similar parts, the carrier generally designated by the numeral 10 and as best illustrated in its erected and applied position, as 40 shown in FIGURE 1, is formed from a blank of paperboard material or other suitably stiff but flexible fibrous sheet material, the blank being provided with suitable folding scores and cuts to define the various elements of the same. In FIGURE 1, the carrier 10 is shown applied to a rectangular parallelepiped object generally designated as 12 which may be a plurality of similar shaped rectangular parallelepiped articles 14, or it may be a single rectangular parallelepiped article of suitable size for accommodation to the carrier.

50 The carrier 10 comprises a top wall 16, a bottom wall 18 and a side wall 20 to which both the top wall and bottom wall are hingedly connected in spaced apart relationship. Top wall 16 includes downwardly depending flanges 22, 24 and 26 extending from its periphery except

55 where the top wall is joined to the side wall 20. The bottom wall 18 is provided with upstanding flanges 28, 30 and 32 about its periphery except where the wall 18 is joined to the side wall 20. Extending upwardly from the junction of the top wall 16 with the side wall 20 is a handle 34 having a suitable finger hole 36.

Referring now to FIGURES 1 and 3, the rectangular parallelepiped object 12 having generally the same volume as the volume defined between the top wall 16, bottom wall 18 and side wall 20 is positioned within the flanges 28, 30 and 32 of the bottom wall and then the side wall is folded into contiguous relationship with the

side object 12. The top wall is folded down into contiguous relationship with the top of the object 12, the flanges 22, 24 and 26 encompassing the top of the object. After this is accomplished, the object 12 may be carried by the carrier as the load imposed upon the carrier by the object when the carrier is lifted by the handle 34 causes the top and side walls 16 and 18, respectively, to have an ice tong action about the object 12 to tightly support the same therebetween. The downwardly depending and upwardly standing flanges bear tightly against the object 12 and hold the top and bottom walls 16 and 18, respectively, in contiguous engagement with the top and bottom of the object.

Referring now to FIGURE 2, it will be noted that the carrier 10 when erected and applied to an object 12 lends itself to easy stacking on the store shelf as the handle 34 does not interfere with the carrier and its object stacked thereon. As shown in broken lines in FIGURE 2, the carrier 10' with its parallelepiped object 12' is stacked on the top wall 16 of carrier 10, the handle 34 of the carrier 10 nesting against the rear side of side wall 20'.

The blank from which the carrier 10 is formed is best illustrated in FIGURE 4 and comprises an integral sheet of appropriate paperboard material or the like suitably cut and having folding scores so as to provide the top wall 16, side wall 14, bottom wall 18 and handle 34. In more detail, the top and bottom walls 16 and 18, respectively, are rectangularly shaped and have the approximate area of the total area of the top and bottom of the rectangular parallelepiped article or articles for which the carrier is constructed. Intermediate the top and bottom walls 18, the blank is provided with the rectangular side wall 20 and two flaps 40 and 42 for forming the handle 34. Side wall 20 is rectangular and has an area approximately the same as the total area of the side wall or walls of the article or articles to be carried.

A folding score line 44 separates the flap 40 from the top wall 16 whereas a folding score line 46 separates the flap 42 from the side wall 20. A folding score line 48 separates the flaps 40 and 42 from each other. As shown in FIGURE 4, the surfaces of the flaps 40 and 42 are coated with a suitable adhesive so that when the carrier is erected and the handle 34 is formed by folding along the score line 48 the flaps 40 and 42 are secured together to give the handle a double thickness. When folded upon the line 48, the flaps 40 and 42 adhere to one another and the folding score lines 44 and 46 lie in substantially contiguous relationship with each other so that effectively the top wall 16 is hingedly connected to the handle 34 and the side wall 20 by the folding score lines 44 and 46.

The flaps 40 and 42 which form the handle 34 are provided with similar cutouts 50 and folding score lines 52. When the handle is formed, the material encompassed by the cutouts 50 may be pressed out along the folding score line 50 to provide the finger opening 36.

Bottom wall 18 is separated from the side wall 20 by a folding score line 54 which is parallel to the folding score lines 44, 46 and 48. The score line 54 provides hinged connection between the side wall and bottom wall after the fold has been made and prior to complete erection of the carrier.

The top wall 16 and bottom wall 18 are identical in construction and are provided about their periphery except where they are respectively connected to the handle 34 and side wall 20 with the flaps for providing the flanges 22, 24, 26, 28, 30 and 32. In more detail, the flanges 22 and 24 are provided on the outer parallel longitudinal peripheral edges of the top wall 16 by folding score lines 56 and 58, respectively. Flanges 22 and 24 have diagonal outer edges 60 and 62, respectively, extending from each of the terminal ends of the score lines 44 to points 64 and 66, respectively. Then the flanges 22

5

and 24 are provided with edges 68 and 70, respectively, which are parallel to the fold lines 56 and 58 so that when the flanges 22 and 24 are folded downwardly they will have a maximum height equal to the height of the end flange 26.

End flange 26 is connected to the top wall 16 by a score line 72, the end flange 26 being provided with end flaps 74 and 76, respectively. In addition, the end flange 26 is provided with a flap member 78 separated therefrom by a score line 80 which is parallel to the score line 72.

The flanges 22 and 24 from the points 64 and 66 are provided with diagonally extending folding score lines 82 and 84, respectively. Adhesive is applied to the areas of the flanges 22 and 24 outwardly of the score lines 82 and 84, respectively, as shown in FIGURE 4, and thus when the end flange 26 is folded downwardly along the score line 72 with its corner flaps 74 and 76 folded at right angles thereto, the flanges 22 and 24 may be folded downwardly along the score lines 56 and 58, respectively, with the adhesive portion thereof securing the side flanges 22 and 24 to the end flange 26 on the end flaps or tabs 74 and 76. After the flanges 22 and 24 have been adhesively secured to the end flaps 74 and 76 of the end flange 26, the flap 78 may be folded on the score line 80 through an arc greater than 90° to a position where it lies within the erected flanges 22 and 24.

Referring to FIGURE 5, a perspective view of a corner formed as described above is disclosed. It will be noted that the flap 76 of the end flange 26 has been secured to the portion of the side flange 24 outwardly of the score line 84. When such a construction is made, the top wall 16 defines a shallow tray-like member with the flanges 22, 24 and 26 depending downwardly therefrom.

As mentioned above, the bottom wall 18 is constructed identically with the top wall 16 and the flanges 28, 30 and 32 are folded and secured together in identically the same manner. Consequently, a description of the folding and securing together of the flanges of the bottom wall 18 is not repeated herein, it being understood that when such flanges are secured together, the bottom wall 18 also forms a shallow tray-like member which opposes the tray-like member of the top wall 16.

As best illustrated in FIGURE 6, after the carrier has been erected by securing together the downwardly depending flanges of the top wall 16 and the upstanding flanges of the bottom wall 18, the carrier, when not in use, may be folded into a substantially flat, rectangular member so that it and plurality of similar carriers may be stored and easily shipped to a point of use. The folded carrier of FIGURE 6 has the side flanges of the top and bottom wall 16 and 18, respectively, folded inwardly along their respective fold lines with the secured together portions of the side flanges and the respective end flanges being folded inwardly along the diagonal fold lines 82 and 84 of the side flanges. This is possible since the portion of the flaps 74 and 76 which extends inwardly of the diagonal fold lines 82 and 84 is not adhesively secured to the respective side flanges 22 and 24 at the point indicated by the letter A.

Referring now to FIGURES 2 and 3, it will be noted that when the articles 12 are placed in the tray-like member formed by the bottom wall 18, the upstanding flanges 28, 30 and 32 encompass a portion around the bottom of the articles 12. Then the side wall 20 is folded about the score line 54 and the tray-like member defined by the top wall 16 and its downwardly depending flanges is slipped over the top portion of the articles 12. The flap 78 of both of the flanges 26 and 32 will assume the position shown in full lines in FIGURE 2 and thus tightly bear against the articles to frictionally engage the same. Prior to applying the carrier to the articles 12, the flaps 78 will assume the position shown in broken lines in FIGURE 2 because of the natural resiliency of

65

70

75

the paperboard material used. By providing the flaps 78 folded in the manner heretofore described and having the natural resiliency to assume the position shown in broken lines of FIGURE 2 when the articles are placed in the carrier 10, the flaps 78 tend to wedge the articles between the same and the side wall 20. Slight variations in the size of the articles carried may be accommodated by providing such a flap construction.

The carrier hereinbefore described functions on the "ice tong" principle in that both the top wall 16 and bottom wall 18 are effectively hinged to the side wall 20 and when the tray-like members defined by these walls encompass the end portions of an article and the carrier is lifted by the handle 34, the weight of the article causes the top wall 16 and bottom wall 18 with their respective flanges to tightly encompass the article.

It will now be seen that the carrier of the present invention accomplishes the objects and advantages as heretofore described, and while a preferred embodiment of the invention is illustrated and described, the structure is susceptible to some changes and modifications without departing from the scope of the invention. Therefore, the terminology used in this specification is for the purpose of description and not limitation, the scope of the invention being defined in the claims.

What is claimed is:

1. A carrier made from paper board material or the like for holding a generally rectangular shaped parallelepiped article or group of articles comprising similar opposed spaced top and bottom walls, a side wall, said top and bottom walls being pivotally joined to and free to pivot relative to said side wall, said top and bottom walls each having flanges extending from the peripheries thereof except where the top and bottom walls are joined to said side wall, said flanges of the respective top and bottom walls each having a height substantially less than the height of said side wall for encompassing opposite end portions of the article or group of articles while leaving a major portion of the article or group of articles exposed, and a handle extending upwardly above the top wall and in generally the same plane as said side wall whereby when said carrier is lifted, weight of the article or articles carried thereby causes the flanges of said top and bottom wall to bear against the article or articles and maintain the top and bottom walls parallel to each other and in contiguous relationship with the opposite ends of the article or articles.

2. A carrier of claim 1 wherein said flanges extending from the peripheries of the top and bottom walls are provided with fold lines whereby the flanges may be folded into substantially flat relationship with said top and bottom walls when said carrier is empty.

3. A carrier of claim 1 including flap members provided on marginal edges of the flanges of said top and bottom walls respectively which are opposed to said side wall, said flap members being folded inwardly toward said side wall and upwardly and downwardly toward the respective top and bottom walls whereby said flap members bear against the article or articles encompassed by the flanges of the respective top and bottom walls.

4. A carrier made from paper board material or the like for holding a generally rectangular shaped parallelepiped article or group of articles comprising similar opposed spaced top and bottom walls, a side wall hingedly connected to said top and bottom walls along respective marginal edges of the same, said top and bottom walls each having flanges extending from the remaining marginal edges thereof, the flanges of the top wall being joined to each other adjacent the corners of the top wall furthest from the side walls and the flanges of said bottom wall being joined to each other adjacent the corners of the bottom wall furthest from said side wall, said flanges of the respective top and bottom wall being arranged to encompass opposite end portions of the article

or group of articles while leaving a major portion of the same exposed, and a handle carried by said side wall, said handle being arranged on said side wall whereby when said carrier is lifted by the handle, the weight of the article or articles carried thereby causes the flanges of the respective top and bottom wall to bear tightly against the article or articles and maintain the top and bottom walls substantially parallel to each other and in contiguous relationship with the opposite ends of the article or articles.

5. A carrier of claim 4 wherein the flanges of the top wall include a pair of opposed side flanges and an end flange, said side flanges each having a fold line extending from the respective corners of the top wall diagonally toward said side wall whereby the joined flanges of said top wall may be folded into substantially flat relationship with the same and wherein the flanges of the bottom wall include a pair of opposed side flanges and an end flange, said last-mentioned side flanges each having a fold line extending from the respective corners of the bottom wall diagonally toward said side wall whereby the joined flanges of said bottom wall may be folded into substantially flat relationship with the same.

6. A carrier of claim 4 wherein said handle is an extension of said side wall and lies in the plane of the same extending outwardly from where the side wall is hingedly connected to the top wall.

7. A carrier of claim 4 including a flap member extending on the outer marginal edge of one of said flanges of said top wall, said flap member being folded inwardly of the flanges and upwardly toward said top wall, and a second flap member extending from the marginal edge of one of said flanges of said bottom wall, said flap member being folded inwardly of the flanges of the bottom wall and downwardly toward the bottom wall.

8. A carrier of claim 4 wherein the flanges of said top wall include a pair of opposed side flanges joined to an end flange, each of the side flanges having an outer marginal edge extending from a point of junction with the end flange diagonally to said top wall and wherein the flanges of said bottom wall include opposed side flanges joined to an end flange, each of the side flanges of said bottom wall having an outer marginal edge extending from a point of junction with the end flange diagonally to said bottom wall.

9. A carrier of claim 4 wherein said handle is an extension of said side wall and lies in the plane of the same extending outwardly from where the side wall is hingedly connected to the top wall, said handle being hingedly connected with respect to said side wall and said top wall.

10. A carrier for similar shaped articles comprising a paper board blank having a plurality of substantially parallel score lines; said blank being folded along said score lines to define a bottom wall, a side wall, a handle and a top wall, said bottom and top wall each being further defined by a pair of parallel score lines extending longitudinally of the blank and folded to define side flanges, each of said top and bottom walls being provided with a transverse score line to define a terminal edge of the same and being folded along the same to define an end flange, and tabs on each end flange whereby said end flange when erected may be fixedly secured to said side flanges so that said top and bottom walls define shallow tray-like members for receiving the end portion of articles to be carried.

11. A carrier of claim 10 wherein each end flange of the respective top and bottom walls is provided with a flap member on its free edge, each flap member being defined by a score line whereby said flap member may be folded inwardly of its respective tray-like member.

12. A carrier for similar shaped articles or the like formed from a single blank and comprising a side wall, a pair of opposed shallow tray-like members hingedly connected to opposite parallel edges of said side wall and a

handle projecting from said side wall, said tray-like opposed top and bottom members being adapted to encompass end portion of the articles being carried to support the same therebetween when the carrier is lifted by said handle.

13. A carrier of claim 12 wherein each of said shallow tray-like top and bottom members is provided with a flap member folded inwardly of an edge of the same for tightly engaging articles to be carried when the tray-like top and bottom members are placed about the end portion of the articles.

14. A carrier of claim 13 wherein each flap member depends from the edge of its respective tray-like member which is opposite the edge of the same connected to said side wall.
